UNITED STATES PATENT OFFICE.

WILLIAM B. SHELP, OF HOUSTON, TEXAS, ASSIGNOR TO MELLIE ESPERSON, OF HOUSTON, TEXAS.

VALVE.

1,145,853.

Specification of Letters Patent.

Patented July 6, 1915.

Application filed October 14, 1913. Serial No. 795,032.

To all whom it may concern:

Be it known that I, WILLIAM B. SHELP, a citizen of the United States, resident of Houston, county of Harris, and State of Texas, have invented a new and useful Improvement in Valves, of which the following is a specification, the principle of the invention being herein explained and the best mode in which I have contemplated applying that principle, so as to distinguish it from other inventions.

My invention relates to valves, and particularly to that type of valves in which resiliency is an essential or desirable characteristic. Valves of this type are largely used in water pumps and in order to procure the required results, such valves should be so constructed as to fit perfectly upon the valve seat at all times and under normal conditions, so as to make a perfect seal and hence prevent leakage, as will be readily understood by those skilled in the art. In the normal operation of a water pump particles of wood, sand, gravel or other hard substances lodge, not infrequently, upon the valve seat and hence, as is obvious, tend to hold the valve from proper contact with such seat, thus permitting leakage, sometimes of considerable extent, when the pressure is reversed and the valve is caused to exercise its checking function. In order therefore to eliminate this leakage, rubber valves have been employed, the resiliency of whose seat-contact surface would permit them to assume an irregular contour presented by an intervening obstruction and in the presence of the latter, make good or even perfect contact with the seat. The use of rubber has also made the valves comparatively silent in their operation, eliminating the "hammering" which is a characteristic of the use of metal valves, and also the breaking of the latter as a result of such "hammering". The rubber valves heretofore used, however, have been subject to certain deficiencies of which lack of rigidity and strength and expense of material have been prominent.

The object of my present invention is to provide a valve for water pumps or other apparatus in which it may be used, which will embody all of the desirable features of rubber valves of the character heretofore

used, which will be of increased efficiency and which will be of lower cost of manufacture.

To that end therefore my invention consists of means hereinafter fully described and particularly set forth in the claims.

The annexed drawing and the following description set forth in detail certain means embodying my invention, the disclosed means, however, constituting but one of various mechanical forms in which the principle of my said invention may be employed.

In said annexed drawing:—Figure 1 is a perspective view of a valve embodying my invention, a part of its structure being illustrated as broken away. Fig. 2 is an axial section of a fragmentary portion of said valve, upon a slightly enlarged scale. Fig. 3 is an axial section on a reduced scale of a typical valve seat structure showing a complete valve in side elevation in connection therewith.

The figures of the drawing illustrate my invention as embodied in an ordinary disk check-valve used in water pumps, in which the valve is provided with a central cylindrical bore 6^a, Fig. 1, for receiving a guide-rod 7, secured to a spider intersecting a valve opening surrounded by a valve seat 8, Fig. 3. The free end of the rod 7 is capped with a nut, and interposed between the latter and the valve proper, is a coil-spring 9 which tends to hold the valve in contact with or move same toward the seat 8, as will be readily understood. The valve-disk, however, instead of being of the usual construction is constructed as follows: A strip of fabric 1 of such length and width, is first taken, as will produce the required dimensions of the finished valve, and which has previously been impregnated with uncured rubber, or "rubberized," as this condition is ordinarily referred to. This process of rubberizing is carried out by means of calenders as is well known to those skilled in the art and hence need not be described in detail herein. The rubberizing is, however, carried to such an extent as to thoroughly impregnate or incorporate the rubber in the fabric and also provide both surfaces thereof with a substantial layer of the uncured rubber. The strip is then wound upon a mandrel to form spiral con-

volutions and finally to form a cylindrical disk of the required dimensions which constitutes the main or body portion of the valve in which those faces containing the dimension of width, are parallel with each other, that is, in which the dimension of width of the fabric is parallel with the axis of the valve. The mandrel is then removed leaving a central cylindrical opening. The entire exterior of the disk is now covered with additional cured rubber to form an outer envelop or casing consisting of the top 3, the bottom 4, the outside 5 and inside 6, of considerable thickness, as shown in Fig. 2. The structure so formed is now placed in a suitable mold and subjected to the usual curing or vulcanizing, during which the disk is closely confined so as to prevent expansion. The application of the heat, the simultaneous confinement of the disk and the resultant pressure causes the raw rubber to liquefy, still further permeate the fabric and the entire mass of rubber to coalesce and form a homogeneous binder, part of which is incorporated in the fabric and which when the rubber cools, unites and secures the adjacent convolutions of fabric to each other. The resultant structure has all of the characteristics of a mass of cured rubber formed into a disk and reinforced by a strip of perforate and flexible material wound to form spiral convolutions separated by intermediate spiral convolutions 2 of rubber. A cross-section of the structure presents, as shown in Fig. 2, alternately occurring layers of fabric 1 and rubber 2, with rubber incorporated in the fabric.

The fabric being flexible does not prevent the disk as a whole from having a certain required degree of flexibility or resiliency and at the same time, being tough and non-elastic, is less liable to rupture, also less subject to wear, and thus increases the strength and life of the valve. The outside of the valve consisting of pure vulcanized rubber, it will be seen that the contact surface thereof has all of the characteristics of a solid rubber valve of the usual construction, and after this casing wears off, a surface having still many of those characteristics remains.

The above described method of construction may be modified by omitting the preliminary rubberizing of the fabric and placing upon the strip of fabric a similar strip of uncured rubber and then winding same spirally to form the main body of the disk. The subsequent vulcanizing process then causes the rubber to flow into the fabric, the resultant product being substantially the same as in the first described process. I have also found it preferable in some cases to cut the fabric used on the bias so that the warp and woof threads thereof will run in a direction angular with respect to the

valve's axis. This angularity of direction is such that each thread forms an angle less than ninety degrees with a line passing therethrough which is parallel with the axis of the valve. By this arrangement an increased resiliency is obtained while retaining the desired physical characteristics of the fabric. 70

A still further modification of said above-described method may be resorted to by taking a sheet of fabric a number of times greater in width than the thickness of the required valve, subjecting it to the rubberizing process, then winding it spirally and very firmly, then cutting it into disks of the required thickness by means of a suitable sharp tool. The outer casing is now applied and the whole vulcanized as before. 75 80

It is obvious that a valve-disk of the above described structure may be secured, in any suitable manner, to a valve stem so as to form a puppet or mushroom valve, the structure in this case forming the valve cap. 85

In the above described manner therefore I obtain a valve construction having all of the characteristics of solid rubber while eliminating many of the objectionable features thereof. The introduction of the fabric also obviously reduces the amount of rubber required in the construction of the valve and thus reduces the cost of manufacture to a material degree. 90 95

Having fully described my invention, what I claim and desire to secure by Letters Patent is:—

1. As a new article of manufacture, a valve comprising in its structure convolutions of flexible material having its dimensions of width extending parallel with the valve's axis. 100

2. As a new article of manufacture, a valve comprising in its structure convolutions of flexible material and intermediate convolutions of elastic material, in which the dimension of width of convolutions extends in a direction parallel with the axis of the valve. 110

3. As a new article of manufacture, a valve having a cross-section presenting alternate layers of flexible and elastic material, the major transverse dimension of said layers running in the direction of the valve's axis. 115

4. As a new article of manufacture, a valve having a main or body portion comprising in its structure convolutions of layers of fabric arranged endwise, the transverse dimension of said layers intersecting the opposite faces of such main or body portion. 120 125

5. As a new article of manufacture, a valve having a main or body portion comprising in its structure convolutions of layers of fabric arranged endwise and intermediate convolutions of rubber, the trans- 130

verse dimensions of each intersecting the opposite faces of such main or body portion.

6. As a new article of manufacture, a valve comprising in its structure convolutions of fabric having its warp and woof threads angularly related to the opposite faces of said valve.

7. As a new article of manufacture, a valve comprising in its structure convolu-

tions of fabric having its warp and woof threads forming angles of less than ninety degrees with respect to lines passing therethrough and parallel with the valve's axis.

Signed by me, this 11th day of Sept., 1913. 15

WILLIAM B. SHELP.
